United States Patent Office

Des. 204,602
Patented May 3, 1966

204,602

ANIMAL TAG

Norman J. Hayes, 2138 Shoshone Trail, Cody, Wyo.

Filed Mar. 23, 1965, Ser. No. 84,406

Term of patent 14 years

(Cl. D12—2)

FIG. 1.

FIG. 2.

FIG. 3.

FIG. 4.

FIG. 5.

FIG. 6.

FIG. 1 is a front elevation of an animal tag embodying my new design;

FIG. 2 is a rear elevation thereof;

FIG. 3 is a vertical section of the tag of FIGS. 1 and 2, taken along line 3—3 of FIG. 2;

FIG. 4 is a front elevation of another embodiment of the design;

FIG. 5 is a rear elevation of the tag of FIG. 4; and

FIG. 6 is a vertical section of the tag of FIGS. 4 and 5, taken along line 6—6 of FIG. 5.

I claim:

The ornamental design for an animal tag, as shown and described.
